Attest;

Fred G. Pilton,

E. E. Wade

Inventor,

Homer F. Livermore;

*A. B. Upshaw,
His Attorney.*

UNITED STATES PATENT OFFICE.

HOMER F. LIVERMORE, OF BROOKLINE, MASSACHUSETTS.

ANTISLIPPING TREAD.

No. 824,994.

Specification of Letters Patent.

Patented July 3, 1906.

Application filed July 28, 1905. Serial No. 271,660.

To all whom it may concern:

Be it known that I, HOMER F. LIVERMORE, a citizen of the United States, and a resident of Brookline, in the county of Norfolk, Commonwealth of Massachusetts, have made certain new and useful Improvements in Anti-slipping Treads, of which the following is a full, clear, and exact description.

This invention relates to a type of tread wherein a comparatively hard plate is formed with circular openings filled with plugs of lead or other antislipping material. This type of tread is usually of malleable cast-iron, with the rims of said openings raised above the remaining surface of the plate in order to permit of considerable wear of the antislipping plugs before the said surface is reached.

The object of my invention is the construction of a tread of this general type in which said raised rims shall be made so hard and wear-resistant as to protect for a largely-increased length of time the soft lead within them and so prolong the life of the treads, for I have discovered that the lead plugs can be protected quite largely by the rims surrounding them without diminishing the antislipping function thereof. In accomplishing this I make the tread-plates from sheet-steel, stamping up the opening rims and hardening them by the combined operations of drawing and compressing.

Referring to the drawings forming part of this specification, Figure 1 is a plan view, on an enlarged scale, of a portion of a tread made in accordance with my invention. Fig. 2 is a sectional view through one of said rims and plugs. Fig. 3 is a sectional view showing the formation of one of said rims, and Fig. 4 is a similar view showing the compression portion of the process.

The numeral 1 designates the tread-plate; 2, the raised rims surrounding the circular openings 3, within which the lead plugs 10 are fixed.

In forming a tread a sheet of low-grade steel of proper thickness, width, and length has punched therein a number of small holes at points corresponding with the desired locations of the lead plugs, the diameters thereof being considerably less than that of the tool 25. (Shown in Fig. 3.) The plate is then laid upon a suitable die 20, having holes 21

therein, the upper part of each of which is equal to the desired outer diameter of the rim flanges 2, while the depth of the shoulder 22 thereof equals the proposed height of said flanges. One of said small holes in the plate 1 being located directly over an opening 21 in the die, the tool or punch 25 is forced downward until the edge surrounding 60 said small hole is brought to the form shown in Fig. 3, but not quite reaching the shoulder 22. This tool is then withdrawn and a tool 26 forced downward into the opening made by the former, its diameter being larger and 65 its nose being cut square across. This second tool acts to depress the rim 2 into contact with the shoulder 22 and to compress between the tool end and said shoulder as an anvil the metal composing the extreme portion of said rim or flange. Said tool 26 is enabled to thus compress said rim by its engagement with the internal shoulder 4, formed during the earlier portion of said tool's descent. By thus strongly compressing 70 the fibers of the steel composing the outer part of each rim or flange the latter is largely increased in hardness and wearing ability. I also find that the earlier step of forcing the metal into the flange form shown in Fig. 3 acts 75 to harden the same, owing to the peripheral elongation given to the outer part of said rim or flange and the consequent radial compression in the same manner that wire is hardened by its elongation and compression in 80 being drawn. Another function performed by the internal shoulder 4 is to prevent the withdrawal of the lead plug after the latter has been introduced within the opening 3 and then compressed, as shown in Fig. 2.

What I claim as my invention, and for which I desire Letters Patent, is as follows, to wit:

1. A tread comprising a sheet-metal plate having openings through it each surrounded with an upstanding rim terminally compressed, and antislipping plugs inserted in said openings and rims.

2. The tread comprising a sheet-metal plate having openings through it each surrounded with an upstanding rim terminally compressed and hardened; and antislipping plugs inserted in said openings and rims.

3. The tread composed of a sheet-metal

plate having openings through it each surrounded with a rim or flange, and antislipping plugs inserted in said openings and rims or flanges; said sheet metal being low-grade 5 steel, and said rims or flanges being terminally hardened.

In testimony that I claim the foregoing in-

vention I have hereunto set my hand this 21st day of July, 1905.

HOMER F. LIVERMORE.
